UNITED STATES PATENT OFFICE.

MATTHEW C. OSTER, OF ROY, MONTANA.

COMBINATION TABLE, STOVE, AND SUPPLY CABINET.

Application filed December 24, 1924. Serial No. 757,879.

This invention relates to an improved apparatus adapted to be used by tourists and under circumstances where a combination table, stove, and supply cabinet is desirable 5 which may be folded into a compact condition.

A further object of this invention is the provision of a foldable table, stove, and supply cabinet device which when folded is 10 substantially rectangular in form, and of such nature that it may be mounted with ease on the running board of an automotive vehicle, or in any convenient position on the vehicle, and in a compact condition, and 15 which may be extended to provide a table having a relatively great table surface, with a stove supported in adjacent relation thereto.

A further object of this invention is the 20 provision of a device of the above mentioned character which includes a collapsible leg structure which when folded will hold the parts of the device in a compact position, and which when extended will support the 25 table at a desired elevation.

A further object of this invention is the provision of a novel type of combination table, stove, and supply cabinet, embodying 30 novel collapsible features by which swingable portions may be used as table leaves, or closures for certain parts of the device.

Other objects and advantages of this invention will be apparent during the course 35 of the following detailed description.

In the accompanying drawings, forming 40 a part of this specification, and wherein similar reference characters designate corresponding parts throughout the several views,

Figure 1 is a perspective view of the improved device in extended position.

Figure 2 is a perspective view of the improved device in extended position, taken 45 from an opposite end with respect to that illustrated in Figure 1.

Figure 3 is a longitudinal cross sectional view taken through the improved combination table, stove and supply cabinet, with the parts thereof extended, this view being taken substantially on the line 3-3 of Figure 1.

Figure 4 is a plan view of the improved device extended.

Figure 5 is a cross sectional view taken 50 substantially on the line 5-5 of Figure 1.

Figure 6 is an end elevation of the improved device extended.

Figure 7 is a view, partly in section, showing the details of the improved device collapsed, and the means by which the legs are collapsed to hold the parts assembled. 60

Figure 8 is a side elevation of the improved device in collapsed relation.

Figure 9 is a cross sectional view taken 65 through the stove casing, with certain closure portions thereof collapsed.

Figure 10 is a fragmentary view, partly 70 in section, showing the end details of the improved device collapsed.

In the drawings, wherein for the purpose 75 of illustration is shown only a preferred embodiment of the invention, the letter A may generally designate the improved combination table, stove, and supply cabinet, which may include a body B; leg supporting means C; stove structure D; and drawer E.

The body B of the improved combination device includes a bottom 15, which may be formed of any approved material, and is preferably rectangular in outline. An end 80 wall 16 is provided in rigid connected relation with the bottom 15, and in right angled upstanding relation therefrom, which has an opening 17 therethrough to slidably receive the drawer E. At the opposite end portion of the bottom 15, a receptacle like 85 supporting wall is provided which includes an end wall 18 affixed in any approved manner upon the bottom 15, in right angled relation thereof, and inwardly from the end edge of said bottom 15. This receptacle like portion also includes the side walls portions 19,

which provide a compartment 20 facing outwardly in open relation at the end of the body B, and adapted to collapsibly receive 90 the stove details D therein, as will be subsequently described. Upwardly of the bottom 15, and supported at its ends by the walls 16 and 18 is a drawer supporting wall 21, which is supported between its ends by means of a transverse partition wall 22,

which divides the compartment within the body B into compartments 23 and 24, and which compartments are adapted to receive supplies of any approved nature. At the 95 upper edges of the walls 16 and 18, and also supported by the side walls 19 is a top wall 26, which provides a plane upper surface.

This top wall 26 is of the same shape and size as the bottom wall 15, and at its end 100 it projects outwardly of the end wall 18 to assist in providing the compartment 20.

From the foregoing discussion it will be 105

110

From the foregoing discussion it will be

noted that the compartments 23 and 24 below the wall 21 are open at the opposite sides of the body B, and extend entirely through the body B, as does also the drawer sliding compartment 28 below the top wall 26.

Closures 30 and 31 are respectively hinged at the opposite longitudinal edges of the top wall 26, in any approved manner, and so that the same may swing upwardly into the same horizontal plane as the top wall 26, or may swing into vertical positions as closures for the side openings of the compartments of the body B. When in such closed position the closures 30 and 31 provide side walls for the body. These closures or side walls 30 and 31 are adapted to be held into their horizontal table forming position by means of wire supporting brackets 32, which are substantially V-shaped in formation, and which are pivoted so that they may swing into the side portions of the compartment in the body, or may swing outwardly of the openings of the compartments of said body, to provide horizontal leg portions upon which the side walls 30 and 31 rest, to provide portions of the table, and substantially as is illustrated in Figure 2 of the drawings. It is preferred to provide two of the brackets 32 for each of the side wall closures 30 and 31, and when these brackets are swung into their respective compartments in the body the closures 30 and 31 swing to provide side walls as is illustrated in Figure 8 of the drawings.

Referring to the stove apparatus D, the same preferably includes a stove casing 35, in the form of an open topped receptacle, providing a compartment 36 therein. This casing 35 is pivoted at 38, adjacent an edge of a rear wall thereof, to the lower portion adjacent an end edge of the body top wall 26, so that the casing 35 may be swung into the compartment 20 of the receptacle like end wall of the body B, into an out of the way relation therein, as is illustrated in Figure 10 of the drawings, or so that it may be swung into horizontal position, as is illustrated in the drawings; the compartment 36 opening upwardly. In this compartment 36 a two burner gasoline stove 39 is provided, of any approved character, which may be fed from a gasoline supply tank 40. The gasoline supply tank 40 may be attached exteriorly of the casing 35, by fitting 41, which may be detached therefrom and placed in the compartment 36 adjacent the stove 39 when it is desired to collapse the stove apparatus in the compartment 20 of the body B. Below the top edges of the walls forming the casing 35, it is preferred to provide racks 42, which may be detachable in character. Hingedly connected at the opposite side walls of the casing 35 it is preferred to provide closure lids 46, which may be swung into a closed rela-

tion over the open top of the compartment 36, as is illustrated in Figure 9 of the drawings, or which may be opened laterally into horizontal position in the same plane as the plane formed by the top wall 26 of the body B, and the side leaves or closures 30 and 31 when extended. In order to provide for the horizontal support of the stove casing, it is preferred to provide sectional collapsible brace arms 48, which at their lower ends are pivoted to the side walls 19 of the receptacle shaped end wall of the body B, and which at their upper ends are pivotally connected adjacent the outer end of the stove casing 35, and which when extended are diagonally positioned to support the stove casing in a horizontal position, as is illustrated in the drawings. These arms 48 collapse into the pocket 20 for the stove casing, between the stove casing 35 and the side walls 19 and are in non-interfering relation with such collapse of the stove casing into the pocket 20, due to the fact that the side walls of the stove casing 35 are divergent.

In order to support the leaves 46 in their horizontal table forming relation, it is preferred to provide pivotal V-shaped bracket arms 50 at each side of the stove casing 35; the same being pivoted to said stove casing, so that they may be collapsed into position along side of the stove casing, or may be extended in right angled relation from said stove casing to support the lids or leaves 46 in the horizontal relation shown. The arms 50 are only of sufficient length that they may be collapsed along side of the stove casing and into the pocket 20. When the stove apparatus B is collapsed it is to be noted that the same is entirely disposed in the pocket 20, with one lid 46 facing outwardly. At the outer surface of this lid 46, it is preferred to provide a handle 52, which when the device is collapsed provides a side handle to assist in carrying of the collapsed device A.

Referring more specifically to the drawer apparatus E, the same includes a drawer body 55, including a bottom wall 56; side walls 57; front wall 58; and rear wall 59. The bottom wall 56 is connected in rigid relation to the side and front and rear walls in a plane upwardly of the lower edges of said side and front and rear walls, so that drawer supporting braces 60 may be pivotally connected to the bottom wall 56, and below a surface thereof, and when collapsed will be disposed immediately below the bottom wall 56, so that the drawer 55 may slide on the lower edges of the side and front and rear walls, upon the drawer supporting wall 21 of the body B; the brackets 60 being positioned in non-interfering relation with the sliding of the drawer when collapsed. The brackets 60 when extended to

horizontally support the drawer 55 at their ends engage the end wall 16 of the body, and at the forward ends thereof provide finger engaging ends 62, to facilitate extension and collapsing of said bracket arms and holding them in their collapsed relation to permit the facile sliding of the drawer 55.

At the top edges of the walls 57 of the drawer 55, it is preferred to rigidly mount 10 lids or leaf sections 65 and 66, which may swing into the compartment of the drawer 55, and in such position that the drawer may be slid into the body B with the leaves 65 and 66 below the top wall 26 of the body B. 15 These leaves or lids 65 and 66 when the drawer 55 is extended are adapted to be swung into horizontal position in the same plane with the wall 26 and the hinged leaves 30 and 31, and so held by means of supporting brackets 68^a, which are provided in hinged connection at the outer surfaces of the side walls 57, and which may be collapsed along said side walls to permit sliding of the drawer 55 into the body B, or 20 which may be extended in right angled relation from the drawer side walls to horizontally support the leaves 65 and 66 as illustrated in the drawings. At the forward surface of the front wall 58 it is preferred to 25 provide a handle 68, positioned on the device A similar to the handle 52 above mentioned, and to facilitate in the carrying of the device A when collapsed, and facilitate opening of the drawer 55.

Referring to the leg supporting construction C, the same is novel in character, and includes supporting legs 70 and 71 hingedly connected at the stove end of the combination device A, and legs 72 and 73 pivotally connected at the drawer end of the device A. These legs are constructed of angle iron, and each of the same has a diagonal brace member 75, which is riveted to a plate portion of the angle leg, and extends for hinged connection at 76^a, on an axis in alignment with the axis of the hinged connection of its respective leg, so that the brace arm 75 moves with the leg. These legs swing outwardly and upwardly along 45 side of the combination device when collapsed. The angle legs are so positioned that when swung upwardly they are disposed at the corners of the collapsed combination device, and the legs 70 and 71 each 50 include a plate portion which overlies the longitudinal edges of the collapsed stove apparatus D, to retain the same in its pocket 20. These legs 70 and 71 furthermore have the other plate portion of each of these legs disposed respectively along the edge portions of the closures 30 and 31, to retain them in a closed position, as is illustrated 55 in Figure 8 of the drawings. In similar manner the legs 72 and 73 are employed for retaining the drawer structure E in a locked

position against detachment when the legs are collapsed at the corners of the device, as is illustrated in Figure 7, and the side plate portions of these legs 72 and 73 also cooperate along the edge margins of the 70 walls 30 and 31 to retain them in a closed and locked position, as is illustrated in Figure 8.

With respect to the legs 70 and 71, the same include pivoted diagonal braces 76 75 and 77 respectively, pivotally connected at their lower ends intermediate the ends of their respective legs 70 and 71, and at their upper ends respectively adapted for receiving pins 78 and 79 in detachable manner to 80 support the legs 70 and 71 in their divergent extended relation, as is illustrated in Figures 1 and 5 of the drawings. In similar manner the supporting legs 72 and 73 are respectively provided with pivoted diagonal 85 brace members 80 and 81, pivoted to the legs 72 and 73 intermediate their ends, and adapted for respectively receiving the pins 83 and 84 in detachable manner, when the legs 72 and 73 are extended, and as is illustrated in Figure 6 of the drawings. It is thus to be noted that the diagonal braces 76 and 77 and 80 and 81 are respectively connected to the pins 78, 79, 83 and 84, when the legs are extended; these pins being carried by the body B. When the legs are collapsed along the corners of the device A, are folded, the diagonal pivoted braces 76, 77, 80 and 81 are of course removed 90 from their respective pins carried by the body B, and when so collapsed the leg diagonal braces are moved into crossed relation as is illustrated in Figure 7 of the drawings, so that the pivoted brace 80 of the leg 72 will then be connected to the pin 100 84, in lieu of its connection with the pin 83, as it was when the leg 72 was extended, and in similar manner the arm 81 is connected with the pin 83. This locks the legs 72 and 73 in vertical supporting relation at the corners of the collapsed parts of the device A, and holds the side leaves of the body B and the drawer apparatus E closed and collapsed against liability of accidental opening. In similar manner the braces 76 and 110 77 are crossed and respectively connected with the pins 79 and 78, when the legs 70 and 71 are folded to hold the side leaves of the body B collapsed and the stove apparatus D in collapsed position in the pocket 20. 115 When the legs are so locked in position the device A is collapsed in a compact relation, and cannot have any of its parts opened until the legs are swung open by removing the respective diagonal braces from the pins 120 125 which they engage on the body B.

In order to insure the proper attachment of the device A, as collapsed, upon some part of the structure which is to receive the same, such as a running board, it is preferred to 130

provide laterally extending lugs 90 and 91 at opposite ends of the body B, contiguous and rigid with the bottom wall 15, and which have openings therein to receive the 5 shanks, bolts or screws or the like, by means of which the device A may be clamped or bolted to the running board or like support.

From the foregoing description of this 10 invention it is apparent that a novel type of combination table, stove, and supply cabinet has been provided, which may be extended to provide a table having a relatively great area, with a gasoline stove supported in proper position at an end of the table, and 15 an open drawer supported at the opposite end thereof. If desired the open top of the drawer may be covered by an additional table leaf. The improved device A provides a drawer which may be subdivided into a 20 plurality of compartments as shown, for properly receiving table accessories such as knives, forks, and other cooking utensils or edibles. The compartments in the body B are open at both sides of the compartment 25 when the leaves 30 and 31 are horizontally positioned, and the brackets which support these leaves are not in interfering relation with respect to access of the materials carried in these compartments. The improved 30 device A when folded is in compact rectangular form, and the handles 52 and 68 may be used to carry the device A. The leg arrangement C is of considerable importance, in view of the fact that the same is 35 very stable for supporting the device when extended, and may serve the additional function of locking the parts of the device A into collapsed relation when said legs are collapsed. For conventional tourists' use 40 the cabinet is but 15 inches in height when collapsed, and the legs when extended provide an additional 15 inches which provides a table the surface of which is 30 inches above the ground surface.

45 Various changes in the shape, size, and arrangement of parts may be made to the form of invention herein shown and described, without departing from the spirit of this invention or the scope of the claims.

50 I claim:

1. A cabinet of the class described comprising a body including a bottom, end walls, a top wall providing a plane surface, said body interiorly thereof providing a compartment open at the sides of said body, side walls hingedly connected to said top wall, bracket means swingable exteriorly of said compartment for supporting the side walls in their horizontal position in the same 55 plane as said top wall to provide a table, said brackets being positioned to collapse within said compartment of the body into an out of the way position to permit folding of the side walls over the open sides of 60 said compartment to close the same, and

legs hingedly connected to said bottom wall adapted to be in position in extended relation to support said body and adapted to swing upwardly at the corners of said body to secure said side walls in closed position. 70

2. In a device of the class described the combination of a body including a bottom wall, upstanding walls, and a side closure, and legs hingedly carried by said bottom wall adapted to swing upwardly in collapsed 75 position against said closure for holding the same in position.

3. In a combination table and cabinet structure the combination of a cabinet supporting body including a substantially rectangular shaped top wall of plane formation, side leaves of plane formation pivotally connected at the opposite longitudinal sides of said top wall, means to collapsibly extend said side leaves into the same plane 80 as the top wall, a drawer slidable at one end of the cabinet body and of a nature to collapse in the cabinet body, or extend therefrom at the end of the cabinet body, plane leaves hingedly connected at the sides of 85 the drawer of a nature to collapse over the drawer for sliding with the drawer into the cabinet body, means to support the last mentioned leaves in extended relation at the sides of the drawer in the same plane as the 90 plane of the top wall and contiguous at the ends of the adjacent side leaves which are hinged to the top wall when the top wall side leaves are extended, a casing collapsibly carried by the cabinet body at the opposite 95 end of said top wall, means to support the casing in extended relation from its adjacent end of the cabinet body, and side leaves 100 pivotally connected at the sides of said casing having means to support the same in 105 extended relation at the sides of the casing in the same plane as the top wall and contiguous at the ends of the adjacent side leaves of the top wall.

4. In a cabinet of the class described the combination of a body providing a bottom wall and compartment through said body, a closure for said compartment at a side of the body, leg means including a supporting leg hingedly connected to said bottom wall, 110 and detachable brace means to secure said leg in extended relation below the bottom wall and into collapsed relation along side of said body in engagement with said closure to lock the closure in shut position. 115

5. In a cabinet of the class described a body including a bottom, upstanding end walls, a top wall, closure means pivotally connected to said top wall adapted to swing downwardly to provide side walls, bracket 120 means for supporting said side walls in horizontal plane formation contiguous with the top wall to provide a table, an article supporting arrangement, means for collapsing the supporting arrangement at an end of 125 130

- 5 said body, means to support the arrangement in extended relation from said end of the body, a drawer arrangement slidably carried by said body, means for supporting the drawer arrangement extended from the opposite end of the body with respect to said article supporting arrangement, and table leaves movably connected with said article supporting arrangement 10 and drawer arrangement including means to support the same in the same plane as the top wall of the body to provide a table surface.
6. In a cabinet the combination of a body 15 providing a compartment opening at an end thereof, leg supporting means for said body, a casing pivotally carried upwardly by said body adapted to swing into the compartment of said body, and means for supporting said casing in extended relation outwardly of said end of the body.
7. In a cabinet of the class described the combination of a body providing a compartment having an opening at a side of the 25 body, closure means for said opening of the compartment, means for supporting the closure means in horizontal position to provide a table so that the compartment is opened, an extensible compartment arrangement collapsible at an end of said body, and leg supporting means mounted to be collapsed to lock said closure and extensible arrangement at the end of said body in collapsed position with respect to the body.
- 30 8. In a cabinet device of the class described a body, collapsible leg supporting means for the body, said body including a compartment opening at an end thereof, a casing pivotally carried upwardly by said body adapted to swing into collapsed relation in said compartment, and closure means carried by said casing.
9. In a cabinet device of the class described a body, collapsible leg supporting means for the body, said body including a compartment opening at an end thereof, a casing pivotally carried upwardly by said body adapted to swing into collapsed relation in said compartment, closure means carried by said casing, and bracket means collapsibly mounted in such compartment adapted to be extended therefrom to support said casing in extended horizontal relation from its compartment.
- 35 10. In a cabinet of the class described the combination of a body providing a compartment opening therefrom, a casing hingedly carried by the body upwardly thereof so that the same may swing into said compartment into vertical collapsed position therein, hingedly connected closure means for said casing, and collapsible leg supporting means carried by the body adapted to be extended therefrom and folded thereagainst to engage and hold the cas-
- ing in collapsed relation within said compartment.
11. In a cabinet of the class described the combination of a body providing a compartment opening therefrom, a casing hingedly carried by the body upwardly thereof so that the same may swing into said compartment into vertical collapsed position therein, hingedly connected closure means for said casing, collapsible leg supporting means carried by the body adapted to be extended therefrom and folded thereagainst to hold the casing in collapsed relation within said compartment, and collapsible brace means carried by the body adapted to be extended for supporting the casing in horizontal extending relation with respect to said body.
12. In a cabinet device of the class described the combination of a body including a top wall providing a plane table surface, said body inwardly of an end thereof providing a compartment, a casing hingedly connected to the top wall of said body adapted to swing into vertical collapsed relation within the compartment of said body, bracket means collapsibly mounted with respect to the body and casing for supporting the latter in extended horizontal relation from its compartment, and hingedly connected table leaves carried by the casing at opposite sides thereof adapted to be positioned in the same plane when opened from the casing and when the latter is extended from its compartment.
13. In a cabinet device of the class described the combination of a body including a top wall providing a plane table surface, said body inwardly of an end thereof providing a compartment, a casing hingedly connected to the top wall of said body adapted to swing into vertical collapsed relation within the compartment of said body, bracket means collapsibly mounted with respect to the body and casing for supporting the latter in extended horizontal relation from its compartment, hingedly connected table leaves carried by the casing at opposite sides thereof adapted to be positioned in the same plane when opened from the casing and when the latter is extended from its compartment, and collapsible leg supporting means adapted to support the body and being collapsible to lock the casing and the table leaves supported thereby in the closed relation within the compartment of said body.
14. In a cabinet of the class described the combination of a body providing a compartment inwardly from an end thereof, a casing pivoted to said body to be swung to vertical collapsed position within said compartment, closure means for the casing, collapsible brace means for extending the casing in horizontal position from said compartment.

ment of the body, said body at the opposite end having a compartment therein, a drawer 5 slidable in said compartment and adapted to be extended therefrom, collapsible legs hingedly carried by said body adapted to be extended therebelow for supporting the body, said legs being swingable upwardly along the body into engagement across said casing and drawer at the ends of said body, 10 and means for locking the legs in collapsed position to hold the casing and drawer in locked relation to the body.

15. In a cabinet of the class described the combination of a body providing a compartment opening at the side thereof and a compartment opening at an end thereof, a closure hingedly connected with said body for the side opening, a casing hingedly carried by said body adapted to be collapsed into 20 the open compartment at the end of the body, means for supporting the closure and casing in extended relation with respect to the body, and supporting legs pivotally connected to the body, one of said supporting 25 legs being formed of angle material and hingedly positioned to fold into collapsed relation at a corner of the body whereby one portion of the angle leg extends into overlapped relation with the closure at the side 30 of the body to hold the same shut and the other portion of the leg extends over the casing at the end of the body to hold the same in shut position within the body.

16. A cabinet of the class described comprising a body including a table top, hingedly connected table leaves at the sides thereof, means for holding the table leaves extended in the same plane as the table top, extensible devices at the ends of said body, table leaves 40 collapsible carried by said devices at the ends of said body, and means for supporting the leaves of said devices in horizontal position in the same plane as the table top.

17. In a cabinet of the class described the combination of a body providing an opening inwardly from an end thereof, a drawer slidable in said opening, a hingedly connected member at the side of said body, means for holding the hingedly connected member extended, and leg means pivotally carried by 50 said body adapted to support the same above a ground surface, said leg means adapted to be collapsed at a corner of said body to lock the hinged member and drawer in closed relation with respect to the body.

18. In a cabinet of the class described the combination of a body including a bottom wall, end walls and a top wall, said body providing a compartment opening at the 60 sides of the same, hingedly connected side leaves carried by the top wall adapted to close over the side openings of said compartment, collapsible bracket means extensible from said compartment to support the 65 side leaves in horizontal relation in the same

plane as the top wall to provide a table therewith, an extensible article supporting casing carried at the end of said body, extensible table leaves carried by said casing adapted to be extended into the same plane 70 as the table top wall in providing a table, and collapsible legs carried by the body extensible therefrom and adapted to collapse at the corners thereof the same being of angle formation to provide portions overlapping the side leaves of the body to hold the same closed over said compartment and including portions adapted to overlap the portions of the article casing to hold the leaves thereof closed thereon and hold the said casing in collapsed relation with respect to the body.

19. In a cabinet of the class described the combination of a body providing an opening inwardly of an end thereof, a device extensible from said opening, legs pivotally carried by said body, said legs being formed of angle iron, hinged brace means carried by the legs adapted to be connected to said body to support the legs in brace extended relation, said legs being collapsible along said body to overlap said extensible device at the end of the body to hold the same collapsed in the body, said brace means adapted to be utilized to lock the legs in collapsed 95 position.

20. In a device of the class described the combination of a body, a device collapsible at an end of the body, brace means for holding the device in extensible position from 100 said body, legs, pins carried by the body, and braces connected with the legs adapted to engage said pins to lock the legs in extending for supporting the body, said brace means being detachable whereby the legs 105 may be positioned in collapsed relation along the body in overlapped relation with the extensible device at an end of the body to hold the said extensible device collapsed in the body, said braces being connected between 110 the legs and said pins to hold the legs collapsed and locked in collapsed relation on said body.

21. In a cabinet device of the class described the combination of a body including a table surface, said body having an opening therein, a drawer slidable in said opening, side leaves pivotally carried by the drawer adapted to be folded therein when the drawer is collapsed in the body to collapse 120 said side leaves with the drawer in said body, and means for supporting the side leaves in extensible relation from said drawer when the drawer is extended to add to the table surface of said body.

125
22. In a cabinet device of the class described the combination of a body including a table surface, said body having an opening therein, a drawer slidable in said opening, side leaves pivotally carried by the drawer 130

adapted to be folded therein when the drawer is collapsed in the body to collapse said side leaves with the drawer in said body, means for supporting the side leaves in extensible relation from said drawer when the drawer is extended to add to the table surface of said body, said body providing a compartment opening at a side thereof, a side leaf hingedly carried by said body upwardly thereof for said compartment opening, means for supporting the side leaf in extensible relation to add to the table surface of said cabinet, and collapsible leg means adapted when collapsed to overlap the side leaf and the drawer when collapsed in the body whereby to lock the side leaf in collapsed positions.

23. In a cabinet device of the class described the combination of a body providing a bottom wall, legs hingedly connected at the corners of the body adjacent said bottom wall, a pair of spaced pins extensible outwardly from an end of the body, a pair of braces one of each being hingedly connected to said legs intermediate its leg ends for engaging the nearest pin to support the legs in extended relation from the body, said legs being collapsible upwardly along the body when the braces are detached from said pins, said braces when the legs are so collapsed being permitted to extend for connection to the most remote pin at its adjacent end of the body whereby to lock the respective legs in collapsed position along said body.

35 24. In a cabinet of the class described a

body including a bottom wall, upstanding end wall structures, a top wall providing a table surface, one end wall providing a drawer compartment therein, a drawer slideable in said compartment, the other 40 wall of said body providing a compartment therein, a stove casing pivotally connected upwardly to the body adapted to be collapsed in said compartment at the said end wall of said body, table leaves 45 hingedly carried by said drawer and stove casing at the sides thereof, means for supporting the side leaves of the drawer and stove casing in horizontal extended relation when the drawer and stove casing are extended and contiguous with the body top wall to widen out the table surface thereof, said body between said end walls providing a compartment opening at the sides of the body, side walls hingedly connected to the 55 top wall of the body for closures for the side openings of said last mentioned compartment, brace means collapsible in the said last mentioned compartment extensible to support the side leaves contiguous with the 60 top wall to widen out the table surface of the cabinet, angle legs pivotally connected at the corners of said body swingable upwardly to overlap the side walls of said compartment when collapsed and the drawer and stove 65 casing when collapsed, and means to lock the legs in collapsed relation to lock the cabinet in collapsed position.

MATTHEW C. OSTER.
